UNITED STATES PATENT OFFICE.

WILLIAM F. MCKAY, OF LA GRANGE, ILLINOIS.

FIBROUS SHEET AND PROCESS FOR MAKING SAME.

1,365,711.

Specification of Letters Patent. Patented Jan. 18, 1921.

Application filed May 29, 1918. Serial No. 237,184.

To all whom it may concern:

Be it known that I, WILLIAM F. MCKAY, a citizen of the United States, and a resident of the city of La Grange, in the county of Cook and State of Illinois, have invented certain new and useful Improvements in Fibrous Sheets and Processes for Making Same; and I do hereby declare that the following is a full, clear, and exact description of the same, reference being had to the accompanying drawings and the numerals of reference marked thereon, which form a part of this specification.

My invention has reference more particularly to a material and the process and machine for making same whereby a composition and fibrous material are combined and formed in a tough, wear and weather resisting sheet suitable for use as a roof, floor or wall covering or a lining for partitions or any similar purpose, and my invention relates to subject matter similar to that of my application filed August 28th, 1917, Serial No. 188,581.

In the manufacture of roofing paper and similar covering and lining material of the class to which my invention relates, it is customary to use a foundation such as a sheet or ribbon of paper, cloth, felt or similar material which is previously prepared and then treated with a tar, asphaltum or other suitable composition to render it weather-proof and impervious to moisture, and in some cases it is also coated and finished either during the process of manufacture or after it is laid ready for use, with a quantity of sand, gravel, mica, talc, crushed slate or other suitable material to provide a wearing surface for the finished product.

So far as I am aware, however, the body or foundation for all such forms of roofing and similar products, and that which gives it its tensile strength is the paper, cloth or felt, and the coating or other surfacing material therefor is provided to render it impervious to moisture and capable of withstanding the wear to which it is subjected. In my invention, however, no such paper, cloth or other fabric is employed, but the sheet is made entirely of a ribbon or sheet of bituminous or other composition with a layer of criss-cross commingled strands of fibrous material bonded together and combined with the ribbon or sheet of composition, so as to afford a tough structure which gives to the finished product a high degree

of tensile strength and impenetrability and obviates the necessity of using a paper, cloth, felt or other material as a foundation or body and results in a sheet of superior quality which is more economical to manufacture than those previously provided.

Moreover, in those cases wherein fibrous material has been employed, heretofore, it has been the practice to first treat and reduce the fibrous material to a pulp, after which it is used in making the paper. Such treatment, however, causes the fibrous material to lose its resistive properties and its capability of being combined in a tough structure, and while this loss was not material in the former manner of using the fibrous material owing to the fact that a foundation of paper, cloth or other material was employed, it is very important in my method of manufacture and I therefore utilize the fibrous material without reducing it to a pulp and without depriving it of its characteristics which enable it to be combined in a tough structure.

There is a wide range of fibrous substance which can be used such as shreds of vegetable or mineral products, or chopped shreds of cloth, paper, rope and the like, but the fibrous material which I prefer to use is straw or some similar fibrous material as it is inexpensive and abundant, and also as it has in its natural state, great water resisting properties as well as a natural ability to resist action of the elements, and if combined in suitable lengths in a criss cross commingled manner and suitably bonded affords a very tough structure.

It is an object therefore of my invention to use straw or other similar fibrous material in substantially its natural state and by the use thereof to make a wear and weather resisting sheet material, without the necessity of using a paper, felt or fabric as a foundation.

It is a further object of my invention to form a sheet of a plastic composition with one or more layers of criss cross commingled strands of straw or other similar fibrous material, suitably bonded and combined with the sheet of plastic composition to toughen and afford tensile strength and impenetrability to the finished product and render it less susceptible to wear and the action of the elements.

It is a further object of my invention to provide a machine for making a ribbon or

sheet of plastic material and combining one or more layers of criss cross, commingled strands of fibrous material therewith and thereafter applying a covering or surfacing material thereto so as to provide a finished product without the use of paper, fabric or felt as a foundation, and which is as strong and durable as similar sheets heretofore made in which a foundation of paper, fabric or felt was required.

My invention also has other important objects which will appear from the following specification and the accompany drawings, in which I have illustrated and described 15 my invention in a preferred form.

On the drawings:

Figure 1 is a diagrammatic side view of mechanism for making my improved fibrous sheet material.

20 Fig. 2 is a fragmentary plan view of a sheet of the material with different layers thereof broken away to show the successive steps in the process of manufacture, and also shows portions of the mechanism for effecting such manufacture.

Fig. 3 is a sectional view taken on the line 3—3 of Fig. 2.

Fig. 4 is an enlarged sectional view showing an initial step in the process of manufacture.

Fig. 5 is a fragmentary top view of the ribbon of composition with the fibrous material thereon.

Fig. 6 is a fragmentary sectional view of 35 the finished product.

As shown on the drawings:

In making my improved fibrous sheet material, a pliable ribbon or sheet of composition is first made, to which the fibrous material is subsequently applied, and in the structure shown there is an endless belt 1, of canvas or other suitable material and of a width somewhat greater than the strip or ribbon of composition to be made, which belt is 40 mounted on the drums 2, suitably spaced and journaled in the standards 3. These drums, together with the drums and rollers hereinafter referred to are operated at a suitable speed to provide and feed the strip of material continuously to and through the various mechanisms of the device, the belt 1, being adapted to have the material deposited thereon in a fluent condition and spread evenly across the surface thereof, to form a 45 ribbon or sheet, care being taken to maintain the belt in such condition and to avoid pressing the material down onto the belt, so that it will not adhere thereto and may readily be fed therefrom to other parts of the device 50 which apply the fibrous material and finish the product. For thoroughly saturating the belt, previous to the deposit thereon of the material of which the ribbon is made, so that the material will not adhere, the upper 55 length of the belt 1, adjacent the outer end

thereof is passed over a pair of rolls 4, and under a pair of rolls 5, which latter rolls are mounted in a tank 6 of water and carry the belt through the water in the tank so that it is thoroughly saturated. After passing 70 through the tank 6, the belt 1, passes under a tank or receptacle 7, containing a bituminous or other suitable composition of which the ribbon or sheet is to be made, the composition being maintained in a fluent 75 condition and applied to the upper surface of the belt 1, by means of a suitable discharge means 8, which deposits the composition on to the upper surface of the belt 1. After passing under the receptacle 7, the 80 belt 1, passes between and carries the composition thereon between the upper and lower spreading rolls 9 and 10, respectively the former of which is maintained at a suitable temperature and provided with adjusting means indicated at 11, so that the material deposited on the belt from the receptacle 7, is spread uniformly across the width of the belt and made into a ribbon. It is necessary in making the ribbon to prevent 85 the material from adhering to the belt, so that it will readily separate therefrom and for this reason the material of which the ribbon is made is flowed or distributed on the surface of the belt in such manner that 90 it is unnecessary to apply pressure to give it a uniform thickness, as this would tend to cause it to adhere to the belt. The roll 9 therefore is arranged and adjusted not to apply a rolling pressure on the material, but 95 to have a spreading effect. As a further means of effecting non-adherence of the ribbon to the belt and to facilitate separation thereof, the belt 1, immediately ahead of the rolls 9 and 10, is passed over a series of rolls 10. 12, which are mounted at the top of the receptacle 13, and dip into the water contained therein so as to keep the belt thoroughly saturated.

At the forward or discharge end of the 110 conveyer belt 1, there is a roll 15, which is elevated above the surface of the upper length of the belt 1, and has the ribbon 14, passed thereover so as to lift the ribbon 14, off the conveyer belt 1, as the belt turns 11. downwardly around the drum 2. The ribbon 14, is then passed through the mechanism comprising the rolls 16, 17 and 18, over and under which the ribbon is looped and rolled so as to work the material of the ribbon to a desired condition preparatory to having the fibrous material applied thereto, and after passing through the rolling mechanism, it is operated on by a trimming mechanism comprising a pair of upper and 120 lower cutter wheels 19 and 20, respectively, at each side of the ribbon, which trim off the rough edges of the ribbon and leave it of uniform width.

The ribbon is then passed under a tank 130

21, which contains a rather thick water-proof adhesive or binding liquid, preferably of bituminous composition which is sprayed or flowed onto the upper surface of the ribbon 14, as indicated at 22, after which the ribbon passes under a receptacle 23, which deposits a layer of fibrous material indicated at 24, on the coating 22, on the upper surface of the ribbon 14. This fibrous material is preferably straw or similar material in substantially its natural condition, and in short pieces varying in length up to several inches or so, which falls on the ribbon in a tangled criss-cross fashion some-
 15 what as shown at 24. After the fibrous material has been applied, the ribbon and material thereon are passed between the rolls 25 and 26, which are maintained at a suitable temperature so as to heat and press or roll
 20 the straw or fibrous material down into the coating 22, so that the straw or fibrous material is thoroughly matted and bonded together by and with the coating and caused to adhere and combine with and embed in
 25 the ribbon as indicated at 27, and the ribbon is then passed around the roll 26, and backward around the roll 28, so that the surface upon which the straw has been deposited faces downwardly and passes over a conveyer 29, so that the surplus straw or fibrous material which has not firmly adhered to the ribbon will be deposited in the conveyer 29, and is carried thereby to another conveyer
 30 30, at the side of the machine, which discharges into the boot 31, of the elevator 32, and is elevated thereby so that it can be again supplied to the receptacles and deposited again upon the belt or ribbon 14.

The quantity of straw or fibrous material with which the ribbon 14, is provided may be varied according to the quantity thereof required for the finished product. However, as the adhesive material or liquid does not readily permeate a mass of straw, it is preferable to apply only so much straw at a time as adheres to the layer or coating of adhesive material and if an additional quantity of straw is desired it is applied in successive layers so as to insure a thoroughly combined mass of straw, and such successive layers may be supplied by a series of mechanisms similar to that which I have just described. In the present illustration I have shown mechanism for providing the ribbon 14, with two layers of the matted straw or fabric, and have shown the ribbon 14, passing from the roll 28, forwardly therefrom under a roll 33, and over a roll 34, and around another set of rolls 35, 36 and 37, similar to the rolls 16, 17 and 18, previously described, and which work the ribbon into suitable condition for further application of fibrous material. The ribbon is then passed under a tank 38, and the receptacle 39, and

through the rolls 40 and 41, over the con- 65 veyer 42, around the roll 43, and the rolls 44 and 45, and around the rolls 46, 47 and 48, all of which are similar to the corresponding parts of the mechanism previously described and act upon the ribbon 14, in a 70 similar manner to provide an additional layer of fibrous material thereon in corresponding steps indicated at 65, 66 and 67. The conveyer 42, similar to the conveyer 29, deposits on the conveyer 30, and carries the 75 surplus material to the elevator 32, so that it may be used over again.

Additional mechanism for providing other layers of fibrous material to the ribbon may be provided if desired, and after 80 fibrous material has been supplied to the desired extent and combined with the ribbon 14, the surface thereof may be coated and finished in any desired manner depending upon the purpose for which the sheet is to 85 be employed. For finishing, an adhesive material is supplied as at 68, to the upper fibrous surface of the ribbon 14, from the receptacle 49, which is placed thereabove, and the ribbon 14, is then passed between the 90 rolls 70 and 71, which spread the coating evenly over the upper surface of the fibrous ribbon, after which the ribbon is passed under a receptacle 50, which deposits on the 95 upper surface of the ribbon, a layer of coating 69, of sand, ground cork, pulverized slate or any other suitable material with which the surface of the sheet is to be provided. Coloring matter may also be applied to give the finished sheeting any color or design which may be desired, and the ribbon 14, is then passed between the rolls 51 and 52, which combine the finishing material with or cause it to adhere securely to the ribbon. 100

If the finished product is to be furnished with a smooth surface and without any configuration, the ribbon may be passed directly from the rolls 51 and 52 to the trimming wheels 53 and 54, arranged in pairs at 110 each side of the ribbon so as to trim off the edges thereof and furnish the sheet in any predetermined uniform width that may be desired, or if it is desired to emboss or finish the sheet with a design on the outer surface 115 thereof, an embossing roll 55, may be mounted adjacent the roll 52, and provided with a suitably embossed or figured surface which rolls against the outer surface of the ribbon 14, and impresses a design in the surface 120 thereof such as shown at 56, or otherwise as may be desired. To prevent clogging of the impression roll 55, and to insure a perfect impression it is desirable that the supply of surfacing material from the receptacle 50 125 shall be regulated so that only sufficient material is deposited to firmly adhere to the ribbon and prevent a surplus thereof being

carried forward loose on the ribbon to the impression roll, or suitable devices, such for instance as rolls arranged as the rolls 26 and 28, previously described, so as to face 5 the ribbon downwardly, may be provided to remove any surplus non-adhering surfacing material previous to the operation of the impression roll 55 on the ribbon. In order that the embossing roll 55, may roll freely 10 against the outer face of the ribbon 14, without sticking, said roll is mounted in the receptacle 58 so as to run continuously in a bath of water contained in the receptacle, and the excess of water which may be carried 15 up in the grooves and crevices of the impression roll 55 is blown away by a blast of air which is furnished by the pipe 57, said pipe being provided at the side thereof next the roll 55, with a narrow slit or a series of 20 perforations extending lengthwise of the pipe which direct the air against the surface of the roll 55, as indicated in Fig. 1. From the roll 52, the ribbon is passed back around a roll 59, thence forwardly under the 25 roll 60, and over the roll 61, which roll together with the various rolls heretofore mentioned, are operated at a substantially similar surface speed so as to advance all parts of the ribbon at a uniform rate, and after 30 passing over the roll 61, the ribbon 14 is guided by means of the support 62 to the cutters 53 and 54, which cut the ribbon into any desired widths and it is then cooled and cut in any desired shapes, widths or lengths. 35 From the foregoing, it will be noted that I have provided a process and a machine whereby a material may be made in sheets without the use of a separate previously prepared paper, cloth or fabric as a foundation 40 and using merely a ribbon of the bituminous or other composition which has one or more layers of straw or fibrous material spread thereon in a criss-cross manner and bonded together and combined therewith so as to 45 strengthen the ribbon and render it capable of resisting wear and the action of the elements; that a wide range of fibrous substances may be used, such as shreds of vegetables or mineral products or chopped shreds 50 of cloth, paper, rope and the like, and that the quantity of the straw or fibrous material applied to the ribbon may be varied to result in a sheet of material of various grades, for different purposes, and that the resultant 55 sheet may be furnished in a plain finish or figured or embossed and colored in any desirable manner.

For the purpose of illustration, I have shown and described my invention in a certain form and explained the process in connection with a certain mechanical structure, but I wish to be understood that I am aware that various changes and modifications may be made in the product, process and mechanisms employed without departing from the

principles of my invention, and I therefore do not purpose limiting the patent granted hereon otherwise than necessitated by the prior art.

I claim as my invention:

1. A weather proof sheet having an outer skin of plastic material, an outer skin of surfacing material and an impregnated and cemented layer of criss cross overlapping strands of straw, bonded together, compressed between and bonded to said outer skins so as to afford tensile strength and impenetrability to said sheet. 75

2. A weather proof sheet having an outer skin of plastic material, an outer skin of surfacing material, and a layer of matted straw compressed between and bonded to said outer skins so as to afford tensile strength and impenetrability to said sheet. 80

3. A weather proof sheet having an outer skin of plastic material, an outer skin of surfacing material, and a layer of criss cross overlapping strands of fibrous material bonded together, compressed between and bonded to said outer skins, said sheet being 85 provided with an ornamental design 90 impressed in the skin of the surfacing material and the layer of fibrous material. 95

4. The process of making a weather proof sheet which consists in spreading a mass of plastic material so as to form a pliable ribbon, then applying a bonding material to the surface thereof, then depositing a layer of fibrous strands in criss-cross tangled relation loosely on the surface of the pliable ribbon, 100 then heating and pressing the fibrous material and bonding material against and into the surface of the pliable ribbon to combine the fibrous material and bonding material therewith so as to afford tensile strength and 105 impenetrability to the pliable ribbon, and then depositing a coating and surfacing material on the layer of fibrous material. 110

5. The process of making a wear and weather resisting sheeting which consists in forming a pliable ribbon from a mass of plastic material, then applying a bonding material to the surface of the ribbon, then depositing a layer of straw loosely onto the bonding material, then applying heat and 115 pressure and rolling the straw against and into the ribbon to combine same therewith, then depositing additional bonding material and a surfacing material on the layer of straw. 120

6. A weather proof sheet consisting of a layer of relatively long pieces of fibrous material arranged in criss-cross and tangled relation, said layer being impregnated, cemented together and coated on both sides 125 with an adhesive, pliable, water-proof material, the constituents of the sheet being bonded together by heat and pressure. 130

7. A weather proof sheet consisting of a layer of cemented and impregnated straw

coated on both sides with a water-proof material.

8. A weather proof sheet consisting of a layer of straw coated with water-proof material which is bonded to the layer of straw by heat and pressure.

In testimony whereof I have hereunto sub-

scribed my name in the presence of two subscribing witnesses.
